Primary Examiner — Christian P. McLean*Assistant Examiner* — Christopher John Suarez La Rosa(74) *Attorney, Agent, or Firm* — Dunlap Bennett & Ludwig, PLLC(57) **CLAIM**

The ornamental design for a travel case with pockets, as shown and described.

DESCRIPTION

FIG. 1 is a front perspective view of the travel case with pockets, showing my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines shown in the drawings depict portions of the travel case with pockets that forms no part of the claimed design.
